UNITED STATES PATENT OFFICE.

ARTHUR H. ELLIS, OF ROCHESTER, MINNESOTA, ASSIGNOR OF ONE-HALF TO CHRISTOPHER GRAHAM, OF ROCHESTER, MINNESOTA.

SIGNAL-CONTROLLING SWITCH.

Application filed August 4, 1927. Serial No. 210,597.

The invention relates to a new and improved switch designed for controlling a plurality of signal circuits on an automobile.

5 One object of the invention is to provide a simple switch mechanism controlled by a push button and operable upon lateral tilting of such button to actuate a signal such as a turning or stop light, but operable upon 10 straight inward forcing of the button to sound the usual horn or other audible signal or warning. One of the signal circuits controlled by the switch will usually be for a parking light brought into play by lateral 15 tilting of the button to one position, and it is a further object of the invention to provide unique means for holding said button in this position so that the parking light may be kept illuminated when desired.

20 Another object of the invention is to provide a rather simple and inexpensive yet a compact and very desirable construction and arrangement of parts which may be readily assembled at the factory, may be partially 25 disassembled with ease when connecting the current conducting wires thereto, and may then be quickly and easily replaced in final assembled condition for use.

In the preferred form of construction, 30 an insulating plug carrying a number of binding posts and conductors, is removably held within one section of the main body of the device by means of a co-acting bayonet slot and stud, and it is another object 35 of the invention to utilize this stud as a portion of the current conducting means brought into play by operation of the push button.

With the foregoing and minor objects in 40 view, the invention resides in the novel subject matter hereinafter described and claimed, the description being supplemented by the accompanying drawings.

Fig. 1 is a side elevation.

Fig. 2 is a longitudinal sectional view.

Fig. 3 is a view similar to Fig. 2 but illustrating the button held in one tilted position, this view being partly in elevation.

Fig. 4 is a detail sectional view showing 50 the horn-operating contacts in engagement with each other.

Fig. 5 is a disassembled perspective view of a number of the parts of the switch.

Fig. 6 is a perspective view showing the

insulating plug juxtaposed with respect to 55 a number of parts carried by it.

Fig. 7 is a plan view of the push button.

In the drawings above briefly described, the numerals 9—10 denote two complementary body sections which jointly form a hollow cylindrical body, said section 9 fitting into the section 10 and having a threaded or other desired connection 11 therewith. This section 9 is preferably of metal and may well be provided with an attaching base 60 12, and when the device is used upon machines having one terminal of the usual battery, grounded to the chassis frame or the like, said body section 9 will be secured to or formed integrally with a metallic portion 65 70 of the machine having electrical conducting relation with said frame or the like.

The body section 10 is formed of insulating material and the outer end of this body section is provided with an opening 13 of 75 non-circular form, for a purpose to appear. Around the periphery of this section, I provide circumferentially spaced contacts 14 which are preferably in the form of screws, the heads of these screws being co-operable 80 with contact means carried by a cupped push button 15, while the inner ends of said screws engage certain conductors hereinafter described. The push button 15 fits loosely over the outer end of the body section 10 and the 85 above-named contact means of this push button is preferably in the form of a cupped metallic shell 16 which constitutes a lining and hence a reinforcement for the push button, as well as constituting a contact. Within 90 the confines of the cupped push button and its shell 16, and secured to the center of said shell, is a current-conducting post 17 of non-circular form. This post passes loosely through the opening 13 and permits both 95 lateral tilting of the push button 15 and straight inward movement of said button.

A coiled compression spring 18 surrounds the post 17 between the shell 16 and the body section 10, said spring serving to normally 100 force the push button outwardly to a predetermined limit. In the present disclosure, this limit is defined by an annular contact 19 disposed within the body section 10 and secured to the post 17 by a screw 20, said 105 post, screw and contact being in electrical conducting relation. The contact 19 projects beyond the periphery of the post 17 and

contacts with the outer end wall of the body section 10, when the button 15 has been moved outwardly under the influence of the spring 18.

- 5 The straight inward movement of the button 15 is relied upon to operate the usual horn or the like, whereas the tilting movement of said button may be utilized to control a stop light, right and left signals 10 and a parking light, as will be clear from the initials on Fig. 7. When this button is tilted, its contact shell 16 comes into engagement with one or another of the contact screws 14 to complete the desired circuit, 15 and in order that said shell may be held in contact with the screw 14 associated with the parking light, I provide the push button with a hook 21 to hook into the kerf of this particular screw, as shown in Fig. 3. 20 Preferably, the hook 21 is integral with or otherwise joined to the shell 16 of the push button.

An insulating plug 22 fits removably within the body section 9 and projects beyond 25 this section into the section 10, said plug being provided with a pair of metallic studs 23 engaged with bayonet slots 24 in said shell section 9, the plug being yieldably held to maintain the studs and slots in engagement with each other by a coiled compression spring 25 which is disposed within the body section 9. Upon slight inward shifting of the plug 22 however, and rotation thereof to some extent, the studs 23 clear the slots 24 30 and said plug may be bodily withdrawn from the body section 9, as will be clear from Fig. 5.

Passing centrally through the plug 22, is a conductor 26 to which to connect the horn wire 27, said conductor being preferably in the form of a bolt, with its head 28 disposed in the inward path of the head 28^a of the screw 20. Surrounding this contact portion 28 of the conductor 26, is an annular contact 29 which is suitably secured within a groove in the outer end of the insulating plug 22, the contact 29 and conductor 26 being insulated from each other by a portion of said plug. As will be clear from Figs. 40 3 and 4, the annular contact 29 is co-operable with the annular contact 19 above described, and said contact 29 is placed in electrical conducting relation with one of the studs 23, by means of a conductor 30 embedded in 45 the insulating plug 22 and preferably formed integrally with said contact 29.

Conductors 31 are secured in grooves 32 formed longitudinally in the periphery of the insulating plug 22, said conductors having portions 31^a exposed at the periphery of said plug for contact with the inner ends 60 of the screws 14, as shown most clearly in Figs. 2 and 3. These conductors 31 are provided with binding posts 33 for the wires 65 34 of the turning and stop signals and the

parking light. These wires 34 and the horn wire 27 are preferably all encased in metallic armour 35.

When the push button 15 is forced straight inwardly, the contacts 28^a-19, simultaneously strike the contacts 28-29 respectively. Then, current flows from the horn wire 27, through the conductor 26, through the contacts 28-28^a, through the contacts 19-29, through the conductor 30 70 and the associated stud 23, and through the body section 9 to the ground. It will thus be seen that this straight inward movement of the button 15 may be used to sound the usual horn.

When the button 15 is tilted to a position at which its contact means 16 strikes one of the contacts 14, current flows to this contact through the associated conductor 31, binding post 33 and wire 34, and flows from 75 said contact 14 through the contact means 16, post 17 and contact 19, to the contact 29, the contact 19 having come into contact with the member 29 upon tilting of the button, as seen in Fig. 3. It will be observed however that this contact 19 does not then engage the contact 28, nor is said contact 28 80 at that time engaged by the horn-controlling contact 28^a, with the result that the horn will not be sounded, although the current 85 for the stop light, the turning signal, or parking light, will be completed, as occasion may demand. It is, of course, understood that from the contact 29, the current passes onto the ground through the conductor 30, 90 associated stud 23, and body section 9.

Whenever it is desired that the parking light shall remain illuminated, it is simply necessary to engage the hook 21 with the contact 14 associated with said light. If 95 desired, an arrangement duplicating this hook or some analogous arrangement, might well be employed for holding the push button in the position to which it is turned for operating a turning signal or a stop light, 100 but for purposes of illustration, one hook 21 to hold the button 15 in one tilted position, will suffice.

Excellent results are obtainable from the general construction herein disclosed. This 115 construction has been rather specifically described, but such description and the specific showing of the drawings, are to be considered as illustrative rather than limiting, as within the scope of the invention as claimed, 120 numerous variations may be made.

What is claimed is:

1. In a signal controlling switch, a body having circumferentially spaced contacts projecting radially from the annular outer surface thereof, an additional contact within said body at one of its ends, said end having an opening, a cupped push button fitting loosely over said end of the body and having contact means for co-operation with 130

5 said circumferentially spaced contacts, said push button having a central post passing loosely through the aforesaid opening and permitting tilting of the button toward any 10 of said circumferentially spaced contacts, a spring around the post bearing against the body and push button to force the latter normally outward, and a contact secured to the inner end of said post, and normally spaced outwardly from said additional contact but being co-operable therewith upon 15 tilting of the push button.

2. In a signal controlling switch, a body having circumferentially spaced contacts 15 projecting radially from the outer annular surface thereof, said body being formed with an opening at one end, a cupped push button fitting loosely over said end of the body, a cupped contact shell secured within 20 said cupped push button for selective engagement with said circumferentially spaced radially projecting contacts upon tilting of the push button, a metallic post centrally secured to said shell and passing 25 loosely through the aforesaid opening, spring means for outwardly forcing the push button to a predetermined extent, a contact on the inner end of the aforesaid post, and another contact in the body cooperable with the 30 post-carried contact but normally spaced therefrom.

3. In a signal controlling switch, complementary body sections jointly forming a hollow cylindrical body, one of said sections fitting within the other and having a 35 bayonet slot, an insulating plug fitting removably within said one section and having a stud engaged with said bayonet slot, a conductor carried by said plug and having 40 a binding post, a contact passing through the side wall of said other body section and engaging said conductor, and a push button mounted on the aforesaid body and having a contact for engagement with the first 45 named contact.

4. A structure as specified in claim 3; said one body section and said stud being metallic, an additional conductor carried by said plug and connected to said stud, an additional contact connected to said additional conductor and carried by said plug, a contact carried by said button for engagement with said additional contact, and conducting means electrically connecting this contact 55 with the second named contact.

5. In a switch, complementary body sections jointly forming a hollow cylindrical body, one of said sections being metallic and having a bayonet slot, an insulating plug 60 fitting within said one body section and having a metallic stud engaged with said bayonet slot, a contact carried by said plug and electrically connected with said stud, a push button mounted on said body, and a contact 65 carried by said push button and disposed

within said body for co-action with the first named contact.

6. A structure as specified in claim 5; said contacts being of annular form, and additional co-acting contacts within the confines of said annular contacts and carried by the plug and push button respectively. 70

7. In a signal controlling switch, a body having a hollow end portion and an opening communicating therewith, circumferentially spaced contacts carried by said body, a cupped push button fitting loosely around said end portion of said body and having contact means for selective engagement with said contacts when the button is tilted, 80 means tiltably mounting said button and embodying a post passing loosely through the aforesaid opening, an additional contact carried by said post, and another contact mounted in said hollow body portion to be 85 engaged by said additional contact when said button is forced inwardly on a straight line, said last-named contacts being normally spaced apart.

8. In a signal controlling switch, a body 90 having a hollow end portion and an opening communicating therewith, circumferentially spaced contacts carried by said body, a cupped push button fitting loosely around said end portion of said body and having 95 contact means for selective engagement with said contacts when the button is tilted, means tiltably mounting said button and embodying a current conducting post passing loosely through the aforesaid opening 100 and in electrical conducting relation with the aforesaid contact means, an annular contact connected electrically with the inner end of the post and disposed within said hollow body portion, a second annular contact 105 mounted in said hollow body portion for engagement with the first named annular contact when the aforesaid button is forced inwardly on a straight line or is tilted, a third contact within the confines of the first 110 named annular contact and in electrical conducting relation therewith, and a fourth contact within the confines of the second annular contact and insulated therefrom for co-action with said third contact only when 115 the push button is forced inwardly on a straight line.

9. In a signal controlling switch, a hollow body formed of complementary sections detachably connected, an insulating 120 plug within one of said sections and projecting beyond the same into other section, a conductor carried by said insulating plug and exposed at the periphery of its projecting portion, a contact passing through the 125 outside wall of said other body section and engaged with said conductor, a cupped push button loosely fitting around said other body section and having contact means for engagement with said contact, and means mov- 130

ably mounting said push button on said body.

10. In a signal controlling switch, a stationary body having circumferentially spaced contacts at its periphery, a cupped push button mounted on the body for tilting in different directions, said button receiving a portion of said body, a contact shell secured within said push button for selective engage-
ment with said contacts according to the direction in which the button is tilted, and a hook carried by said shell for engagement with one of said contacts to hold the shell in engagement therewith when desired.

15 In testimony whereof I have hereunto affixed my signature.

ARTHUR H. ELLIS.
